Harry Lewis, Valhalla, N. Y., assignor to
Lion Ribbon Co., New York, N. Y.

Application January 5, 1955, Serial No. 33,845

Term of patent 7 years

(Cl. D80—9)

To all whom it may concern:

Be it known that I, Harry Lewis, a citizen of the United States of America, residing at Valhalla, county of Westchester, and State of New York, have invented a new, original, and ornamental Design for a Package Display Stand, of which the following is a specification, reference being had to the accompanying drawing, forming part thereof, wherein:

I claim:

The ornamental design for a package display stand, substantially as shown.
